SADDLE SEAT

David A. Laird, Detroit, Mich.

Application May 26, 1950, Serial No. 10,207

Term of patent 3½ years

(CL. D15—8)

To all whom it may concern:

Be it known that I, David A. Laird, a citizen of the United States, residing at Detroit, in the county of Wayne and State of Michigan, have invented a new, original, and ornamental Design for a Saddle Seat, of which the following is a specification, reference being had to the accompanying drawing, forming a part thereof.

In the drawing:

Figure 1 is a top plan view of a saddle seat, showing my design;

Figure 2 is a side elevation of the saddle seat shown in Figure 1;

Figure 3 is a front elevation of the saddle seat shown in Figure 1; and

Figure 4 is a perspective view of the saddle seat shown in Figure 1.

I claim:

The ornamental design for a saddle seat, as shown.

DAVID A. LAIRD.
